L. B. GRASBERGER

PAPER ROLL HOLDER

Filed Apr. 3, 1922

Inventor
Lawrence B. Grasberger
by Herbert W. Jenner,
Attorney.

UNITED STATES PATENT OFFICE.

LAWRENCE B. GRASBERGER, OF RICHMOND, VIRGINIA.

PAPER-ROLL HOLDER.

Application filed April 3, 1922. Serial No. 549,038.

To all whom it may concern:

Be it known that I, LAWRENCE B. GRASBERGER, a citizen of the United States, residing at the city of Richmond, in the State of Virginia, have invented certain new and useful Improvements in Paper-Roll Holders, of which the following is a specification.

This invention relates to holders used in stores for supporting rolls of wrapping paper so that they can be revolved; and it consists in the novel construction and combination of the parts hereinafter fully described and claimed which permit the roll to be revolved with facility, and to have the papers torn or separated from it in sheets of any desired length.

In the drawings, Figure 1 is an end view of a roll holder constructed according to this invention. Fig. 2 is a front view; and Fig. 20 3 is a plan view, of the same. Figs. 4 and 5 are respectively a side view and a plan view of one of the arms which support the blade, drawn to a larger scale. Fig. 6 is a cross-section through the arm, taken on the 25 line 6—6 in Fig. 4.

The roll of paper 7 is supported by a frame having a main portion 8 formed of a single metal bar bent to form three sides of an oblong figure. The bottom of this part 30 8 has inwardly projecting feet 9 which are arranged parallel to its top member 10 which extends crosswise between its side portions. Foot bars 12 are arranged crosswise of the frame and are secured at their middle parts 35 to the upper sides of the feet 9, and have cushions 14 of india rubber secured to their end portions, and adapted to support the frame on a store counter. A crossbar 15 is secured between the two feet 9, and 16 are 40 the rivets which secure the crossbar and the foot bars to the feet. A frame constructed in this way is light and rigid, and is very inexpensive to manufacture in large quantities.

U-shaped bearing brackets 17 are secured 45 to the sides of the frame, and the center shaft 18 of the roll is journaled in suitable antifriction bearings 19 supported in these brackets.

A blade 20 is provided for separating the 50 papers into sheets, and is pivoted to the top member 10 of the frame by forked brackets 21, arms 22, and pins 24, the said brackets being secured to the underside of the top member and projecting downwardly. The blade 55 rests against the periphery of the roll parallel to its axis, and it is very desirable that its

end portions should bear with equal pressure on the roll, which is often not truly cylindrical, otherwise a sheet torn hastily from the roll will have a ragged edge, and will often not tear off in a straight line.

In order to permit the blade to twist to suit the roll, the arms 22 are formed of spring sheet metal, and their main parts are bent around to tubular or channel-shaped form. These arms have flat ends 25 which are secured to the blade, and eyes 26 for engaging with the pivot pins. The arms are stiff and strong, but their ends 25 twist freely on the axes of the bars and with relation to the eyes 26.

The blade may have one or more corrugations 27, if desired, so that its end portions may twist freely with relation to each other, and so that the blade will otherwise be stiff 75 and strong.

The blade is pressed against the roll by two helical springs 30 secured at one end to pins 31 which project laterally from the arms 22, and at the other end to pins 32 on the side portions of the frame above the level of the pivot pins 24. The springs normally extend diagonally of the side portions of the frame, and project below the pivot pins 24. When the blade is raised, as shown in dotted lines in Fig. 1, to insert a new roll of paper, the springs bear against the edge of the top member and are bent, and the springs then sustain the blade and the arms in the raised position.

The main portion 8 of the frame can be a plain flat bar in cross-section, as shown, and for large and long rolls it can have any approved flanges or corrugations which will strengthen and stiffen it.

What I claim is:

1. In a roll holder, a supporting frame for the roll, brackets depending from the top member of the frame between its sides, arms pivoted to the said brackets, a blade secured to the said arms and adapted to bear on the roll, and helical springs arranged between the said arms and the sides of the frame and secured to the said sides above the pivots of the arms and to the arms below their pivots, said springs normally operating to press the blade downwardly on the roll and being bent by contact with the top member of the frame when the blade is raised pivotally to a point above the level of the top member so that they support the blade in its raised position.

2. In a roll holder, a supporting frame for

- the roll, arms formed of spring sheet metal and pivoted to the frame at one end, and a blade having its end portions secured to the other ends of the arms, the said blade having 5 a longitudinal rib which prevents it from bending and permits it to twist, and the main portions of the said arms being incomplete tubes in cross-section so that they do not bend but are free to twist, thereby permitting 10 the said blade to bear uniformly at all parts of its edge upon an unsymmetrical roll.
3. In a roll holder, a supporting frame for the roll, arms pivoted to the frame and formed of spring metal with their main 15 parts bent around their axes to form torsion springs so that their ends can twist relatively to each other, and a blade secured to the

arms and adapted to bear on the roll, said spring arms operating to permit the end portions of the blade to twist to suit the 20 irregular surface of the roll.

4. In a roll holder, a supporting frame for the roll, arms pivoted to the frame and formed of sheet spring metal, said arms having eyes at one end and flat end portions at 25 the other end and having intermediate portions of incomplete tubular form which form torsion springs and permit their flat end portions to twist relatively to the said eyes, and a blade secured to the said flat end portions 30 and adapted to bear on the roll.

In testimony whereof I have affixed my signature.

LAWRENCE B. GRASBERGER.
